UNITED STATES PATENT OFFICE.

EDWARD W. ANDERECK, OF ALGOMA, WISCONSIN, ASSIGNOR TO THE ALGOMA FLY NET COMPANY, OF ALGOMA, WISCONSIN, A CORPORATION OF WISCONSIN.

TIPPING-MACHINE.

1,150,324.

Specification of Letters Patent. Patented Aug. 17, 1915.

Application filed November 12, 1914. Serial No. 871,733.

To all whom it may concern:

Be it known that I, EDWARD W. ANDERECK, a citizen of the United States, residing at Algoma, in the county of Kewaunee and State of Wisconsin, have invented certain new and useful Improvements in Tipping-Machines, of which the following is a specification, reference being had to the accompanying drawings.

10 This invention relates to certain improvements in tipping machines and has relation more particularly to a device of this general character especially designed and adapted for use for applying metal tips to the ends 15 of cord lengths to prevent the strands of such cords from unraveling; and an object of the invention is to provide a tipping machine having novel and improved mechanism whereby the tips may be applied in a 20 convenient and effective manner with a minimum of labor and within a minimum of time.

It is also an object of the invention to provide a novel and improved machine of 25 this general character including the stationary die and a rotary member coacting therewith, said rotary member being provided with severing means for the metal and for the cord.

30 Furthermore, it is an object of the invention to provide a machine of this general character having novel and improved means whereby a plurality of tips may be applied at a single operation.

35 The invention consists in the details of construction and in the combination and arrangement of the several parts of my improved tipping machine whereby certain important advantages are attained and the 40 device is rendered simpler, less expensive and otherwise more convenient and advantageous for use, all as will be hereinafter more fully set forth.

The novel features of the invention will 45 be carefully defined in the appended claims.

In order that my invention may be the better understood, I will now proceed to describe the same with reference to the accompanying drawings, wherein—

50 Figure 1 is a front elevational view of a tipping machine constructed in accordance with an embodiment of my invention; Fig. 2 is a side elevational view of the device as herein disclosed; Fig. 3 is a top plan view

of the device as herein disclosed, with certain of the parts omitted; Fig. 4 is a view, partly in elevation and partly in section, of the rotary member herein embodied; Fig. 5 is a fragmentary view, partly in section and partly in elevation, illustrating certain features of the invention as herein included; Fig. 6 is a fragmentary view in elevation of one of the circular members herein embodied; Fig. 7 is a fragmentary view, partly in elevation and partly in section, illustrating the controlling means for the operating shaft; and Fig. 8 is a fragmentary view, partly in elevation and partly in section, of the inner face of the driving pulley.

As disclosed in the accompanying drawings, 1 denotes a bed plate having projecting upwardly therefrom adjacent one extremity, the spaced standards 2 having suitably secured to the inner faces thereof the circular members 3. The opposed faces of the members 3 are spaced one from the other and within such space is positioned the rotatable disk 4 fixed to the shaft 5 having one extremity disposed through the axial center of the members 3 and having its opposite extremity suitably supported by the bearing 6 carried by the bed plate 1.

Each of the members 3 is provided in its periphery with a pocket or recess 7, the pocket of one member being in transverse alignment with the pocket of the second member. In each of the pockets or recesses 7 is adapted to be received a die 8 provided in its end faces with a slot or groove 9 adapted to register with a similar groove 10 produced in the periphery of the member 3 and intersecting the pocket or recess 7, as is believed to be clearly shown in the accompanying drawings. In order to maintain the die in proper position within the pocket or recess, I have threaded through the outer face of the member 3 the clamping screw 11 adapted to coact with the die in a manner which is believed to be self-evident.

Operatively supported by the standards 2 and overlying the forward portion of the members 3 and the disk 4 is a guard 12 provided with a forwardly directed extension or arm 14 on which the cords to be tipped are initially supported. By this arrangement, it will be readily perceived that the operator is enabled, with convenience and facility, to position a cord within the

grooves 9 and 10 of the members 3 so that the same will overlie the disk 4 interposed between said members 3.

Each of the members 3 is provided at a point rearwardly of its axial center with an upstanding arm 15 received within a socket 16 formed within the member 3. Coacting with the arm 15 are the clamping members or screws 17 of conventional form threaded through the outer face of the member and coacting with the arm in a manner which is believed to be self-evident.

Adjacent their upper extremities the arms 15 are provided with the aligned openings 18 in which are mounted the trunnions 19 projecting laterally of the rock member 20 of arcuate formation, the forward extremity of said member being provided with the depending spaced male dies 21 adapted to 20 coact with the dies 8, hereinbefore referred to. The opposite extremity of the rock member 20 is provided with an anti-friction member 22 adapted to engage the cam member 23 suitably secured to the periphery 25 of the disk 4 at a predetermined point thereon and adapted to be engaged by the high point 24 of said cam whereby the male dies 21 will be forced within the grooves 9 of the dies 8 to initially bend the wires W, as indicated at 25, it being understood that the cord is placed within the grooves 9 and 10 after the bends 25 have been effected. The anti-friction member 22 is held in contact with the cam 23 and the male dies 21 30 are maintained normally in elevated position through the medium of the retractable member 26, herein disclosed as a conventional coil spring, having one extremity suitably secured to the rock member 20 adjacent the forward extremity thereof and the opposite extremity of the member 26 being suitably anchored to the forwardly projecting arm 27^a carried by the upright 28. The upright 28 is supported by a bar 45 40 connecting the upper extremities of the arms 15. The upright 28 has also projecting forwardly therefrom the arm 30 through the outer or free extremity whereof is threaded the stop screw 31 with which the forward extremity of the rock member 20 is adapted to engage and whereby the movement of the rock member 20 under the influence of the retractable member 26 is controlled.

55 Rotatably supported by the upper extremity of the upright 28 are the spools 32 adapted to contain the supply of wire W, and said wire is directed from the spools 32 over the forward face of the cross arm 27 suitably secured to the forward end of the arm 27^a. The wire W is also disposed beneath the tension springs 33 carried by said cross arm 27. The wire W is then directed through an opening 34 in the rock member 60 65 20 immediately adjacent a die 21 so that

the free extremity of the wire may be forced within the coacting groove 9, it being understood that the operating face of the die is disposed on a desired curvature and preferably semi-circular in cross section.

70 At a predetermined point in its periphery the disk 4 has its marginal portion cut-away and within such cut-away portion is mounted a knife 35 adapted to sever a cord C at a point between the dies 9, as is believed to be self-evident, and immediately adjacent the knife 35 the disk is provided with the transversely disposed knife 36 adapted to force the wire W around the cord C and to sever such wire and at the same time to force the extremities of the wire below the operating edges of the dies 21, as indicated at 37, in order that the next operation may be proceeded with.

75 80 85 For the successful operation of my improved device, I find it essential to provide automatic means whereby the shaft 5 will be caused to stop after having made one complete revolution, for purposes which are believed to be clearly apparent to those skilled in the art to which my present invention appertains. In order to accomplish this function, I loosely mount on the outer extremity of the shaft 5 the pulley 38 adapted to be coupled with any suitable source of 90 power and having its hub 39 provided with an inwardly disposed sleeve 40 adapted to overlie the central extension 41 of the disk 42 keyed to the shaft 5. The inner surface of the sleeve 39 is provided with the ratchet 95 teeth 43 which are adapted to coact with a pawl 44 fixed to a shaft 45 rotatably supported in a marginal portion of the disk 42 and normally maintained in such engagement through the medium of the retractable member 46 secured to the periphery of the disk 42 and to the outer extremity of an arm 47 secured to the opposite extremity of the shaft 45. Pivotedly engaged with the bearing 6 is a trip 48 which is normally maintained in the path of the arm 47 through the medium of the spring 49 and whereby it will be readily perceived that when such arm 47 contacts with the trip the dog 44 will be disengaged from the sleeve 40 which thus 100 105 110 assures the automatic stopping of the shaft at the completion of one revolution.

115 120 125 As herein embodied, the trip 48 is in the form of a bell lever and has secured to its outer extremity the rod 50 which is operatively engaged with the foot lever 51 whereby it will be perceived that upon the operator tapping the foot lever the trip 48 will be disengaged from the arm 47 and a further revolution of the shaft 5 permitted. While not essential, I find it of advantage to assist the action of the spring 49 by the 130 135 expansible member 52 properly positioned below and coacting with the foot lever 51. I also find it of advantage to provide the

marginal portion of the inner face of each of the members 3 immediately in advance of the groove 10 with the recess 3^a so that the severed ends of the cord will not catch between the adjacent faces of the members 3 and disk 4.

From the foregoing description, it is thought to be obvious that a tipping machine constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice.

I claim:

1. A device of the character described comprising two stationary dies disposed in spaced relation, the opposed faces of said dies being recessed, coacting dies movable

relatively to the first mentioned dies, and a rotary cutter movable in a plane between the first mentioned dies.

30

2. A device of the character described comprising two stationary dies disposed in spaced relation, coacting dies movable relatively to the first mentioned dies, a rotary cutter movable in a plane between the first mentioned dies, means for imparting rotation to the cutter in a single direction, and means for controlling such rotation.

35

3. A device of the character described comprising two stationary dies disposed in spaced relation, coacting dies movable relatively to the first mentioned dies, a rotary cutter movable in a plane between the first mentioned dies, means for imparting rotation to the cutter in a single direction, and means for limiting the rotation of the cutter to a single revolution.

40

In testimony whereof I hereunto affix my signature in the presence of two witnesses.

EDWARD W. ANDEREGG.
